C. S. WACKERMAN

Des. 165,498

NARROW WOVEN FABRIC

Filed March 31, 1951

Charles S. Wackerman ^{INVENTOR}

UNITED STATES PATENT OFFICE

165,498

NARROW WOVEN FABRIC

Charles S. Wackerman, Bridgeport, Conn., assignor to The American Fabrics Company, Bridgeport, Conn.

Application March 31, 1951, Serial No. 14,682

Term of patent 7 years

(Cl. D3—32)

To all whom it may concern:

Be it known that I, Charles S. Wackerman, a citizen of the United States, residing at Bridgeport, in the county of Fairfield, State of Connecticut, have invented a new, original, and ornamental Design for a Narrow Woven Fabric, of which the following is a specification, reference being had to the accompanying drawing, forming part hereof.

The drawing shows a face view of a piece of narrow woven fabric embodying my design.

I claim:

The ornamental design for a narrow woven fabric, substantially as shown.

CHARLES S. WACKERMAN.
